UNITED STATES PATENT OFFICE.

JOHN DAGGETT, OF ELYRIA, OHIO, ASSIGNOR OF ONE-HALF TO MORGAN H. LANDERS, OF ELYRIA, OHIO.

DEVICE FOR REINSULATING ELECTRIC AND AERIAL TELEPHONE OR OTHER CABLES.

SPECIFICATION forming part of Letters Patent No. 727,756, dated May 12, 1903.

Application filed November 14, 1902. Serial No. 131,365. (No model.)

To all whom it may concern:

Be it known that I, JOHN DAGGETT, a citizen of the United States, residing at Elyria, in the county of Lorain and State of Ohio, have invented a new and useful Device for Reinsulating Electric and Aerial Telephone or other Cables, of which the following is a specification.

My invention relates to a device for reinsulating telephone and other electric cables that are suspended in air and in which for some cause the original insulation has become imperfect and the cable impregnated with water and from which the water needs to be expelled and the cable-strands reinsulated without taking the cable down.

The object of my invention is to provide a portable device that can be suspended underneath the cable at any desired point and admit of the water being expelled from the cable, the strands of the cable reinsulated, and after any portion of the cable has been treated moved along lengthwise of the cable, as may be desired. I accomplish these objects by means of the mechanism illustrated in the accompanying drawings, in which—

Figure 1 is a side elevation of my invention applied to the messenger or supporting cable of a telephone or other cable. Fig. 2 is a top or plan view of my invention, and Fig. 3 is a transverse sectional view of Fig. 1 in the dotted lines X X.

Similar letters refer to similar parts throughout the several views.

A represents the messenger or supporting cable by which the telephone-cable is supported and to which my device is attached. d represents the telephone-cable, which is supported by the messenger-cable and hangs underneath same.

B represents a narrow trough, preferably of metal, deeper in the center than at the ends and of any convenient width to receive the telephone-cable and wider in the center to more readily absorb heat from below.

Near the center and underneath the trough B is attached a suitable receptacle b for receiving and holding a lamp, gasolene-furnace, or other heating device. This receptacle is closed on all sides, but provided with doors or other devices on the sides, through

which the lamp or other heating device may be introduced, and with a series of small holes or other openings near the top for the escape of the products of combustion. Near the ends of the trough are attached supporting bars c', to the outer ends of which are attached bifurcated or forked suspension-pieces c. The upper ends of these suspension-pieces are provided with a series of parallel holes. The forked ends of these pieces c may be of any desired length and extend up on opposite sides of the telephone or other cable and the messenger-cable. Between the forked ends of the pieces c is placed a grooved pulley-wheel C, provided with a pin, which may be inserted through any of the series of holes in the ends of the pieces c and said pulley-wheel, and thereby support the entire device on said pulley-wheels and messenger-cable. By means of the series of holes in the pieces c the trough B can be held at any desired distance below the messenger or supporting cable A.

The operation of my invention is as follows: The trough B is supported at any desired convenient distance below the messenger-cable. The attachments connecting the telephone or other cable are removed sufficiently to admit of its dropping down into the trough B. The insulating material is then placed in the trough in such amount as may be necessary, paraffin-wax being the insulating material most generally used. Heat by means of a lamp or furnace is introduced in the receptacle b and the heat therefrom communicated through the bottom of the trough to the insulating material in said trough and thence permeating all through the strands of the cable therein, whereby all moisture and water is driven off in vapor and the insulating material permeates and fills up all the space between the strands of said cable. Said cable is then removed and my device run along by the pulley-wheels to any other section or entirely detached, as may be desired.

Having fully described my invention and its operations, what I claim as new, and for which I desire to obtain Letters Patent of the United States, is—

1. In a device for insulating aerial cable-
